(57) **CLAIM**

The ornamental design for a grip for electronic device case, as shown and described.

DESCRIPTION

FIG. 1 is a top front perspective view of a grip for electronic device case showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a bottom rear perspective view thereof;

FIG. 9 is a bottom front perspective view thereof, shown with an electronic device in broken lines to show example environment; and,

FIG. 10 is a bottom rear perspective view thereof.

The dashed broken lines showing an electronic device in FIGS. 9 and 10 illustrate environment and form no part of the claimed design. The remaining dashed broken lines in the figures depict portions of the grip for electronic device case that form no part of the claimed design.

The bracket shown in FIG. 9 indicates an association of components; the bracket forms no part of the claimed design.
